(57) **CLAIM**

The ornamental design for a control box for a displacement pump, as shown and described.

DESCRIPTION

FIG. 1 is a first isometric view of a control box for a displacement pump;

FIG. 2 is a second isometric view of the control box;

FIG. 3 is a third isometric view of the control box;

FIG. 4 is a fourth isometric view of the control box;

FIG. 5 is a top plan view of the control box;

FIG. 6 is a bottom plan view of the control box;

FIG. 7 is a front elevational view of the control box;

FIG. 8 is a left side view of the control box; and,

FIG. 9 is a right side view of the control box.

The broken lines in the Figures are represent portions of a control box for a displacement pump and of a displacement pump and form no part of the claimed design.

1 Claim, 7 Drawing Sheets
